UNITED STATES PATENT OFFICE.

FRANK D. BRISSE, HENRY P. BLUMENAUER, AND EDWIN C. MEYER, OF WORCESTER,
MASSACHUSETTS.

CAR HEATER.

Application filed January 22, 1926. Serial No. 83,083.

This invention relates to a heater, particularly designed for the well-known Hudson car. The principal objects of the invention are to provide a heater for receiving the fresh air as it is drawn through the radiator by the fan and the forward motion of the car, passing the air over the exhaust manifold in such a way as to heat the car efficiently and retain the heat in the air until it can be distributed in the car; also to provide a conductor constituting a necessary part of the heater located at the top of the exhaust pipe elbow so that the air will be heated further at this point.

Other objects of the invention are to form the heater in three parts of cast iron to add to the efficiency by retaining the heat in the cast iron walls, and to provide a heater which can be applied to a Hudson car without cutting or altering any part of the car except the rubber floor mat. Incidentally by causing the air current to be carried along the surface of the manifold, a little is added to the cooling effect on the engine.

The invention is also designed to provide for a very simple and inexpensive construction and especially a very simple way of mounting it on the engine. Other objects and advantages of the invention will appear hereinafter.

Reference is to be had to the accompanying drawing, in which:

Fig. 1 is a side view of a heater constructed in accordance with this invention and applied to a Hudson car;

Fig. 2 is a plan of the same;

Fig. 3 is a view of the register taken in the direction of the arrow 3 in Fig. 1;

Fig. 4 is a sectional view of the same on the line 4—4 of Fig. 3, and

Fig. 5 is a sectional view of the stove on the line 5—5 of Fig. 2 showing the outline of the exhaust manifold in elevation.

In the application of this invention advantage is taken of the fact that the air circulated by the fan, and also the outer air current due to the motion of the car, passes backwardly along the exhaust manifold of the engine. In order to take advantage of this current of air, we confine it and deliver it at the desired point for heating the interior of the car. We employ as a stove for the heater, a casting 10 which is provided with two clips 11 and 12, pivoted to its front edge, which is vertical, and bolted rigidly to the wall of the manifold. These are sufficient to hold the stove in position, but we provide a strap 13 bolted to the top of the engine, bent down so as to engage the top of the inner edge of the stove, near the engine, to keep the stove from vibrating at that point. This simply holds down the inner edge of the stove.

The stove itself consists of a casting as stated which has a flat top and vertical side walls. There is no bottom or rear wall except a short wall 14. The edges of the vertical wall rest on the manifold and seal the stove at that point. The air enters through an inlet opening 15 provided in a reduced portion of the casting and directly open to the air currents as indicated in the drawings. The air necessarily passes along in the stove casting, being concentrated therein and held so that it comes in contact with the manifold and is heated materially in its course through the stove.

At the outlet end the stove is provided with an opening between the wall 14 and the opposite front wall into which projects the end 16 of a pipe 17, which is also formed as a casting, but has all four walls so as to conduct the heated air from the stove to the car. This casting does not have to be fastened to the stove but its discharge end is made to fit in the right hand drive hole in the toe board of the car. At that end it enters the car far enough to steady it there. The casting 17 is located so as to rest on the top of the exhaust pipe elbow with which the engine is provided.

As the pipe passes into the car through the drive hole and through a hole made in the rubber mat, it is provided with a plate 20, also of cast iron, secured to the pipe by screws 30. This plate is held against the rubber which it squeezes at its edges and it closes the open end of the pipe 17. It is provided with a discharge opening 21 which is adapted to be closed by an adjustable slide 22 having a knob 23 passing through a slot 24 in the plate 20. The knob has a spring 25 to hold the plate 22 in any desired adjusted position. Thus the register may be opened or closed or left in an intermediate position as may be desired.

It will be seen that, by making this heater in three parts of cast iron, the air is protected from the products of combustion and conducted into the interior of the car by

active currents which insure its distribution in the car. Also it will be sufficiently heated during its passage from one end of the engine to the other. The stove is secured in place in the simplest possible manner and can be removed readily if necessary. It occupies no extra space likely to be used for other things or ordinary repairs and has no projection on the inside of the car that would 10 be in the way. It is capable of fine regulation.

Although we have illustrated and described only a single form of the invention and shown it is designed for a Hudson car, 15 we are aware of the fact that modifications can be made therein by any person skilled in the art without departing from the scope of the invention as expressed in the claim. Therefore, we do not wish to be limited to 20 all the details of construction herein shown and described but what we do claim is:

In an automobile heater, a cast iron frame having a width enabling it to be supported on the top of the manifold of an engine and having a top surface located below the top 25 of the engine, said frame being open throughout the bottom and rear sides so as to receive heat from the manifold and the engine through these sides when in position, of means on the vertical front wall extending down to the adjacent front wall of the manifold and bolted thereto for holding it thereto, and a clip bolted to the top of the engine and extending down along the side thereof and engaging the top of the frame at 30 a point at the open rear side thereof to hold the heater down at the rear.

In testimony whereof we have hereunto affixed our signatures.

FRANK D. BRISSE.

HENRY P. BLUMENAUER.

EDWIN C. MEYER.
